US00D841623S

(12) **United States Design Patent** (10) **Patent No.:** **US D841,623 S**
Nugent et al. (45) **Date of Patent:** **** Feb. 26, 2019**

(54) **LOUDSPEAKER SYSTEM**

(71) Applicant: **Harman International Industries, Incorporated**, Northridge, CA (US)

(72) Inventors: **Tim Nugent**, Santa Monica, CA (US); **Andy Flint**, Santa Clarita, CA (US)

(73) Assignee: **Harman International Industries, Incorporated**, Northridge, CA (US)

(**) Term: **15 Years**

(21) Appl. No.: **29/616,971**

(22) Filed: **Sep. 11, 2017**

Related U.S. Application Data

(63) Continuation of application No. 29/551,710, filed on Jan. 15, 2016, now Pat. No. Des. 797,078.

Primary Examiner — Paula Allen Greene*(74) Attorney, Agent, or Firm* — Plumsea Law Group, LLC(57) **CLAIM**

The ornamental design for a loudspeaker system, as shown and described.

DESCRIPTION

FIG. 1 is a perspective view of a loudspeaker system showing our new design;
FIG. 2 is a front elevational view thereof;
FIG. 3 is a side elevational view thereof, the opposite side elevational view being a mirror image thereof;
FIG. 4 is a rear elevational view thereof;
FIG. 5 is a top perspective view thereof;
FIG. 6 is an enlarged view of FIG. 1;
FIG. 7 is an enlarged view of FIG. 2;
FIG. 8 is an enlarged view of FIG. 3;
FIG. 9 is an enlarged view of FIG. 4; and,
FIG. 10 is a perspective view thereof, the column tweeter is mounted directly on a main body housing, shown in unclaimed broken lines, without an extension and with the top cover in a closed position.
The broken line showing depicts environmental features and forms no part of the claimed design.

1 Claim, 10 Drawing Sheets(56)
